[57] **CLAIM**

The ornamental design for cordless handset and stand
telephone unit, as shown and described.

DESCRIPTION

FIG. 1 is a left side, top and front perspective view of a
cordless handset and stand telephone unit showing my
new design cradled in its stand;

FIG. 2 is a rear and top perspective view thereof;

FIG. 3 is a front, top and right side perspective view
thereof;

FIG. 4 is a bottom plan view thereof;

FIG. 5 is a left side, top and front perspective view of
the stand of the telephone unit in FIG. 1;

FIG. 6 is a front, bottom and left side perspective view
of the handset of the telephone unit shown in FIG. 1;
and

FIG. 7 is a right side, bottom and front perspective view
of the handset shown in FIG. 1.

For clarity of representation, and convenience of illustration,
the handset and stand of the telephone unit are
shown separately in FIGS. 5, 6 and 7.

FIG. 2

FIG. 3

FIG. 4

FIG. 6

FIG. 7
